UNITED STATES PATENT OFFICE.

PRESTON B. SOUTHWORTH, OF MARYSVILLE, CALIFORNIA.

BUCKLE.

SPECIFICATION forming part of Letters Patent No. 510,824, dated December 12, 1893.

Application filed May 25, 1893. Serial No. 475,486. (No model.)

To all whom it may concern:

Be it known that I, PRESTON B. SOUTHWORTH, a citizen of the United States, and a resident of Marysville, in the county of Yuba 5 and State of California, have invented certain new and useful Improvements in Buckles; and I do hereby declare the following to be a full, clear, and exact description of the invention, such as will enable others skilled in the art to 10 which it appertains to make and use the same.

This invention relates generally to buckles, and particularly to an improved harness buckle, and is adapted for use upon traces, check reins, &c.

15 The object of the invention is to provide a simple and inexpensive buckle, by means of which a strap can be easily adjusted as desired. I have shown my buckle as applied to the end of a trace, but it may be applied to 20 other parts of the harness equally as well.

In the drawings forming a part of this specification: Figure 1, is a view showing it applied to the trace. Fig. 2, is a sectional view, and Fig. 3, is a perspective view of the 25 buckle detached.

I will now describe the buckle in detail. It is made of any suitable metal and is cast in one piece. In construction it comprises the Y shaped piece A, the end or cross bars B, 30 connecting the ends of said side pieces, the central bar C, carrying a vertical tongue D, and the lower cross bar E, which connects the lower ends of the side pieces. These side

pieces may be made in other shapes, but the same relative position of the cross and central bars is maintained. 35

In practice, a strap F, is passed between the center and bottom bar. It is then turned back, passed under one end bar, over the center bar, and under the opposite end bar, the 40 tongue engaging one of the holes in said strap. By this means, a strap can be quickly and easily shortened or lengthened, as desired.

Having thus described my invention, what 45 I claim is—

A buckle comprising oppositely disposed, Y-shaped side pieces, with upper upwardly inclined arms having their ends connected by cross bars, a lower bar connecting the lower 50 reduced ends of said Y-shaped side pieces, and a central upper bar, extending from the crotch of one side piece to that of the other and having an upwardly projecting stud, the said bar carrying the stud, being below the 55 level of the cross bars connecting the ends of the arms of the side pieces, substantially as described.

In testimony whereof I have signed this specification in the presence of two subscribing 60 witnesses.

PRESTON B. SOUTHWORTH.
